UNITED STATES PATENT OFFICE.

LOUIS CLÉMENCET, OF WEST HOBOKEN, NEW JERSEY, ASSIGNOR TO GEORGE K. BIRGE, OF BUFFALO, NEW YORK.

DESIGN FOR WALL-PAPER.

SPECIFICATION forming part of Design No. 24,900, dated November 12, 1895.

Application filed October 15, 1895. Serial No. 565,805. Term of patent 3½ years.

To all whom it may concern:

Be it known that I, LOUIS CLÉMENCET, a citizen of the United States, residing at West Hoboken, in the county of Hudson, in the State of New Jersey, have invented and produced a new and original Design for Wall-Paper, of which the following is a specification, reference being had to the accompanying drawing, showing a part thereof.

10 The design consists of a series of panels formed of ornamental scrolls with festoons of flowers and leaves attached to said scrolls, and in the center of said panels are arranged smaller panels formed of ornamental scrolls 15 and containing groups of figures in the Watteau style, as represented in the accompanying drawing.

The border of the design is also formed of a series of ornamental panels formed of ornamental scrolls with a large vase of flowers 20 and leaves in the center of said panels, as shown in the drawing.

What I claim is—

The design for wall paper herein shown and described.

Witness my hand this 4th day of October, 25
1895.

LOUIS CLÉMENCET.
